(57) **CLAIM**

The ornamental design for steel nose quick change bit holder, as shown and described.

DESCRIPTION

FIG. 1 is a right side elevational view of a first embodiment of the steel nose quick change bit holder showing my new design.

FIG. 2 is a back side elevational view of the first embodiment thereof,
FIG. 3 is a left side elevational view of the first embodiment thereof,
FIG. 4 is a front elevational view of the first embodiment thereof,
FIG. 5 is a bottom plan view of the first embodiment thereof,
FIG. 6 is a top plan view of the first embodiment thereof,
FIG. 7 is a right side elevational view of a second embodiment of the steel nose quick change bit holder, the only difference being the shape of the conical nose, with all other features being the same,
FIG. 8 is a back side elevational view of the second embodiment thereof,
FIG. 9 is a left side elevational view of the second embodiment thereof,
FIG. 10 is a front elevational view of the second embodiment thereof,
FIG. 11 is a bottom plan view of the second embodiment thereof,
FIG. 12 is a top plan view of the second embodiment thereof,
FIG. 13 is a right side elevational view of a third embodiment of the steel nose quick change bit holder, the only difference being the shape of the conical nose, with all other features being the same,
FIG. 14 is a back side elevational view of the third embodiment thereof,
FIG. 15 is a left side elevational view of the third embodiment thereof,
FIG. 16 is a front elevational view of the third embodiment thereof,
FIG. 17 is a bottom plan view of the third embodiment thereof; and,
FIG. 18 is a top plan view of the third embodiment thereof.
